Primary Examiner—Louis S. Zarfas**Attorney, Agent, or Firm—Banner, Birch, McKie & Beckett****[57] CLAIM**

The ornamental design for a bladder for a shoe sole, as shown and described.

DESCRIPTION

FIG. 1 is a perspective view of a bladder for a shoe sole showing my new design;
 FIG. 2 is a top plan view thereof;
 FIG. 3 is a bottom plan view thereof;
 FIG. 4 is a front view thereof;
 FIG. 5 is a rear view thereof;
 FIG. 6 is a left side elevational view thereof;
 FIG. 7 is a right side elevational view thereof;
 FIG. 8 is a cross-sectional view taken along the line 8—8 of FIG. 2;
 FIG. 9 is a perspective view of a bladder for a shoe sole showing an alternate embodiment of my new design;
 FIG. 10 is a top plan view thereof;
 FIG. 11 is a bottom plan view thereof;
 FIG. 12 is a front view thereof;
 FIG. 13 is a rear view thereof;
 FIG. 14 is a left side elevational view thereof;
 FIG. 15 is a right side elevational view thereof; and,
 FIG. 16 is a cross-sectional view taken along the line 16—16 of FIG. 10.
 The broken line showing of a shoe in FIGS. 1 and 9 is for illustrative purposes only and forms no part of the claimed design.

FIG. 1
